(57) **CLAIM**

We claim the ornamental design for a seating for a transport vehicle, as shown and described.

DESCRIPTION

FIG. 1 is a top perspective of our new design for a seating for a transport vehicle in an upright configuration;

FIG. 2 is another top perspective view thereof;

FIG. 3 is a top view thereof;

FIG. 4 is a bottom view thereof;

FIG. 5 is a front view thereof;

FIG. 6 is a rear view thereof;

FIG. 7 is a side view thereof;

FIG. 8 is an opposite side view thereof;

FIG. 9 is a top perspective of our new design for a seating for a transport vehicle in a reclined configuration;

FIG. 10 is a top view thereof;

FIG. 11 is a bottom view thereof;

FIG. 12 is a front view thereof;

FIG. 13 is a rear view thereof;

FIG. 14 is a side view thereof; and,

FIG. 15 is an opposite side view thereof.

The broken lines form no part of the claimed design.

1 Claim, 15 Drawing Sheets
